CLAIM

The ornamental design for a rotary refrigerator for the cooling of fodder pills made by a pill press, as shown and described.

DESCRIPTION

FIG. 1 is a perspective view of the rotary refrigerator for the cooling of fodder pills made by a pill press embodying my new design;

FIG. 2 is a perspective view of the rotary refrigerator from the opposite side;

FIG. 3 is a top plan view thereof; and

FIG. 4 is a bottom plan view thereof.

FIG. 1

FIG. 2

FIG. 3

FIG. 4
